OIL SPRAYING DEVICE

Filed Aug. 11, 1924

Patented Oct. 25, 1927.

1,646,839

UNITED STATES PATENT OFFICE.

THOMAS W. STONE, OF FORT WAYNE, INDIANA, ASSIGNOR TO WESTERN GAS CONSTRUCTION COMPANY, OF FORT WAYNE, INDIANA, A CORPORATION OF INDIANA.

OIL-SPRAYING DEVICE.

Application filed August 11, 1924. Serial No. 731,416.

The invention relates to gas making apparatus, such as carburetted water gas sets and has for its objects to provide a water cooled oil spray of novel and improved construction and arrangement, which is designed to be used in conjunction with the elements of the apparatus during the manufacture of water gas and the like.

During the steam run or gas making period in the cycle of operation of a water gas set, oil is sprayed into the carburetor for the purpose of enriching the blue water gas, which passes over into the carburetor from the generator. This may be accomplished by lowering the oil spray into the carburetor and opening the valve in the oil line leading to the spray. The valve in the oil line is opened and closed at the proper intervals to admit the required amount of oil at a predetermined rate of flow. After passing through the valve, the oil is carried by the oil pipe line to the spray head, where the oil is atomized into and mixed with the blue gas that enters the carburetor from the generator. At the termination of the gas making period the oil supply is cut off by closing the valve and in the event that the oil spray is not water cooled, it is generally raised up or removed from the carburetor during the air blasting period when no oil or steam is passing through, and the spray is replaced in position for the succeeding "run" at the termination of the blasting period. If not properly cooled or otherwise protected from the heat in the manner described, the sprays soon corrode and become plugged up, with the result that the spray of oil is seriously affected and impaired. If the oil spray is of a movable character certain disadvantages are present in that stuffing boxes, swivel joints or flexible hose are required, all of which are highly susceptible to leakage, resulting in loss of oil as well as an appreciable fire hazard. These faults also impair the general efficiency of the apparatus and the quality of gas produced.

In order to eliminate the disadvantages hereinabove stated an object of the present invention is to provide a self-contained water cooled oil spray which when clamped on the carburetor of the gas making set, is designed to remain in its operative position during both the blasting and gas making periods.

A further object of the invention is to

provide a water cooled oil spray of a highly efficient character, composed of few parts of economical manufacture, and which when assembled results in a complete and self-contained unit capable of convenient and secure attachment on the carburetor of a gas making set, and which may be readily removed when desired for cleaning or repairs.

A further and important object of the invention is to provide an oil spray of the character described which is readily adjustable to various degrees of insertion within the carburetor of the gas making apparatus, according to the requirements of manufacture.

In addition to the general objects recited above, the invention has for further objects such other improvements and advantages in construction and operation as are found to obtain in the structures and devices herein-after described or claimed.

In order to make the invention more clearly understood there are shown in the accompanying drawings means for carrying the same into practical effect, without limiting the improvements, in their useful applications, to the particular constructions which, for the purpose of explanation, have been made the subject of illustration.

In said drawings:

Figure 1 is a vertical sectional view through the upper portion of the carburetor of a water gas set and showing a water cooled spray constituting a preferred embodiment of the invention, in position 90 thereon.

Fig. 2 is a side elevation of the assembled oil spray illustrated in Fig. 1.

Fig. 3 is a transverse section on line 3—3 of Fig. 1; and

Fig. 4 is an enlarged detail view in vertical section of the oil spray head.

Referring to the drawings, 1 indicates the upper portion of the carburetor of a gas making apparatus, which may be of any desired or preferred construction and which is preferably provided with a dome 2 having positioned thereon a cover plate 3. The plate 3 is provided with a central depressed portion 4 surrounding an aperture 5 through which the cylindrical water jacket 6 of the oil spray unit is adapted to loosely project. The jacket 6 may be constructed of a piece of steel pipe having at its lower end a welded-in bottom portion 7, centrally aper-

tured as at 8 to permit the spray of oil therethrough into the carburetor. The upper portion of the cylindrical water jacket 6 has welded or otherwise rigidly secured thereto 5 a pair of diametrically opposed upwardly projecting bolts 9 which are suitably threaded at their upper ends. The oil supply pipe 10 is adapted to project downwardly into the jacket 6 and has threaded onto its lower end 10 a spray head 11 having a nozzle portion 12 adapted to register with the aperture 8. The oil supply pipe 10 communicates with the usual valve controlled oil supply (not shown) and has welded or otherwise permanently secured thereto an apertured plate 13 having diametrically opposed ears or lugs 14 which are apertured as at 15 to loosely receive the upper ends of the threaded bolts 9. A gasket 16, preferably of copper, is interposed between the spray head 11 and the bottom 7 of the pipe or jacket 6 and it will be apparent that by drawing down on the nuts 17 the spray head may be clamped tightly down upon the gasket 16 to provide 25 a water-excluding engagement with the bottom of the water jacket.

A split collar 18 is adapted to be securely and adjustably clamped in any desired position on the jacket 6 by means of the bolts 19 30 passing through the apertured ears 20 of the split collar member and secured thereto by the nuts 21. The split collar is provided with a lower annular flange portion 22 adapted to nest within the central depressed portion 4 of the cover plate 3 and the assembled oil spray unit may be rigidly secured in position by means of the bolts 23 and nuts 23^a, the former being threaded or otherwise secured at their lower ends to the cover plate 40 3 on opposite sides of the depressed portion 4, and having loosely fitted thereupon a pair of clamping members 24. When the spraying unit is assembled the cylindrical jacket 6 projects loosely downward through the aperture 5 of the cover plate 3 and by tightening 45 the nuts 23^a the ends of the clamping members 24 are drawn securely down upon the annular flange portion 22 of the split collar member 18, a suitable packing or gasket 25 50 such as copper and asbestos, being interposed between the collar and the cover plate to insure a fluid tight seal.

It will be apparent that the construction described permits of any distance of insertion 55 of the oil spray into the carburetor by reason of the adjustability of the collar 18 on the jacket or pipe 6. The oil spray unit may be removed from the carburetor for cleaning or repairs by loosening the nuts 60 23^a and turning the clamping members 24 approximately 90 degrees to release their ends from engagement with the collar 18.

The water supply for the jacket 6 is admitted from an inlet pipe 26 projecting 65 downwardly into the jacket and is controlled

by the valve 27; and a water outlet port 28 located near the upper portion of the jacket 6 may be connected to any desired point of discharge.

The conventional spray head 11 comprises 70 an upper portion 29 suitably apertured and threaded for the reception of the lower end of the pipe 10. A reduced portion 29^a is threaded for engagement with the lower member 30 or the head. An intermediate 75 member 31 for atomizing and promoting the spray of oil is interposed between the members 29 and 30 of the head, and a gasket or packing member 32 is provided to insure a fluid tight union between said members. 80 The lower member 30 of the spray head is formed with a reduced oil spraying aperture 32 and a shouldered portion 33 designed to register with the aperture 8 in the bottom of the water jacket 6. A second shouldered portion 34 is preferably provided for engagement with the gasket 16.

It will be apparent that the construction and arrangement above described provides an efficiently cooled, rigid and self-contained 90 oil spray unit, which is susceptible of convenient adjustment for any distance of insertion and which may be readily removed from the apparatus when desired for cleaning or repairs. The device is composed of few parts which when assembled, positively insure against the leakage of water from the jacket, or gas or fluid from the carburetor.

What I claim is:

1. In a gas making apparatus, the combination of a carbureter and an oil spraying device comprising a vertically disposed cooling jacket removably secured to said carbureter, an oil supply pipe having a spray head removably contained within and adapted to be drawn against to frictionally abut said jacket, means for removably securing said jacket to said carbureter, and means for removably securing said oil supply pipe to said jacket. 100

2. In a gas making apparatus, the combination of a carbureter and an oil spraying device comprising a vertically disposed cooling jacket removably secured to said carbureter, an oil supply pipe removably contained within and adapted to be drawn against to frictionally abut said jacket, means for adjustably securing said jacket at various distances of insertion within said carbureter, and means for removably securing said oil supply pipe to said jacket. 110

3. In a water gas making apparatus, the combination of a carbureter and an oil spraying device comprising a cooling jacket, an oil supply pipe removably contained within said jacket and having a spray head adapted to register with an aperture in said jacket, a collar adjustably mounted on said jacket, means carried by said jacket for drawing said spray head down upon the 120 125 130

aperture in said jacket, means for removably securing said collar and said jacket to said carbureter, and means for supplying cooling fluid to said jacket.

- 5 4. In a water gas making apparatus, the combination of a carbureter and an oil spraying device comprising a cooling jacket having an aperture therein and having an inlet and outlet for a cooling fluid, an oil
10 supply pipe adapted to be removably contained within said jacket, a spray head mounted on the lower end of said oil supply pipe and adapted to register with said aperture, sealing means interposed between

said spray head and said aperture, means 15 for securing said oil supply pipe to said jacket, said securing means operating to draw said spray head into tight registering engagement with said aperture, a collar adjustably mounted on said jacket, and 20 clamping means mounted on said carbureter and engaging said collar, whereby said jacket and said oil supply pipe may be removably secured at various lengths of insertion within said carbureter. 25

In witness whereof I have hereunto set my hand.

THOMAS W. STONE.
